UNITED STATES PATENT OFFICE.

SAMUEL A. MAIN, OF DANBURY, CONNECTICUT.

HAT-POUNCING MACHINE.

SPECIFICATION forming part of Letters Patent No. 436,061, dated September 9, 1890.

Application filed January 15, 1890. Serial No. 336,987. (No model.)

To all whom it may concern:

Be it known that I, SAMUEL A. MAIN, a citizen of the United States, residing at Danbury, in the county of Fairfield and State of Connecticut, have invented certain new and useful Improvements in Hat-Pouncing Machines; and I do hereby declare the following to be a full, clear, and exact description of the invention, such as will enable others skilled in the art to which it appertains to make and use the same.

My invention relates to hat-pouncing machines.

Heretofore hat-pouncing machines have been constructed with the cone in a horizontal or upright position, which is objectionable for the reason that in the horizontal position the hat-body will not remain on the cone unless held by the hand of the operator or by a device constructed for that purpose, and in the upright position the lathe cannot be belted directly from the shaft, but requires either gear, corner-belting, or beveled friction-pulleys, which create greater friction and are more complicated and expensive. Another objection to these constructions is that the work-line is at an angle of forty degrees, or nearly so, requiring the strength of the operator to be applied sidewise, and such strength can only be maintained for a short period, while in my device the hat-body will remain on the cone and the work-line is level, or nearly so, which enables the operator to apply not only the power of one arm, but of both, with the weight of the body, if desired.

Therefore the object of my invention is to construct a cheap, simple, and durable pouncing-machine wherein the lathe can be belted directly from the shaft and the pouncing-cone held or placed in any desired position between a horizontal and perpendicular, either fixed at some particular angle or capable of adjustment to different positions; and to this end the nature of my invention consists of constructions and combinations, all as will hereinafter be set forth in the specification, and particularly pointed out in the claims, reference being had to the accompanying drawings, in which—

Figure 1 represents a sectional side view, 50 and Fig. 2 a side view of another application of my invention.

A represents the frame of the machine, having its front legs *a* of greater length than its rear legs *a'*, and upon which is secured an inclined top or bed-plate *a²*; B, the lathe-bed secured to the inclined top or bed-plate *a²*, and its sides or arms *b* extending upward; C, the shaft journaled in the sides or arms *b* of the lathe-bed B, and having a pulley *c* fixed 60 thereon, by means of which it is belted directly from the main shaft; D, the pouncing-cone fixed to the end of the shaft C.

To enable the cone to be adjusted to any position desired between a horizontal and perpendicular, the inclined top or bed-plate *a²* is hollowed to correspond to the rounding 65 of the lathe-bed B, which is secured thereon, and the lathe-bed B is provided with a slot *b'*, into which is inserted a bolt *d* for the purpose of adjusting the lathe-bed to the angle desired. The end of the bolt *d* passes through 70 the inclined top or bed-plate *a²*, and when the cone is at the angle desired it is secured by means of a thumb-nut *d'* on the end of the 75 bolt.

What I claim is—

1. In a hat-pouncing machine, the combination of, a frame, a lathe-bed placed at an angle to the frame, a power-shaft secured to 80 said bed on substantially the same angle as the angle of the bed, and a pouncing-cone on one end of the shaft, substantially as set forth.

2. In a hat-pouncing machine, the combination, with the power-shaft journaled in the 85 arms of the lathe-bed and having a pouncing-cone on one end, of the frame, the lathe-bed having a slot in its bottom, and means, substantially as described, for securing said power-shaft and lathe-bed in any angle desired, substantially as set forth.

In testimony whereof I affix my signature in presence of two witnesses.

SAML. A. MAIN.
